GAME DEVICE

Elaine G. Vigan, 1932 Weepah Way,
Hollywood, Calif. 90046

Filed June 10, 1969, Ser. No. 17,622

Term of patent 14 years

Int. Cl. D21—01

U.S. Cl. D34—5

FIG. 1.

FIG. 2.

FIG. 1 is a top plan view of a game device embodying my new design;

FIG. 2 is a side elevational view of the same.

The present design comprises a circular cover having peripheral apertures through which indicia from three rotating discs of varying diameter mounted on a square base may be seen.

I claim:

The ornamental design for a game device, as shown and described.
